D. GUELBAUM.

CONTINUOUS CURRENT BLOWER OR HAND PUMP.

APPLICATION FILED MAR. 26, 1921.

1,411,016.

Patented Mar. 28, 1922.

INVENTOR.

David Guelbaum.

UNITED STATES PATENT OFFICE.

DAVID GUELBAUM, OF SYRACUSE, NEW YORK.

CONTINUOUS-CURRENT BLOWER OR HAND PUMP.

1,411,016.

Specification of Letters Patent. Patented Mar. 28, 1922.

Application filed March 26, 1921. Serial No. 455,720.

To all whom it may concern:

Be it known that I, DAVID GUELBAUM, a citizen of the United States, and a resident of Syracuse, in the county of Onondaga and State of New York, have invented a certain new and useful Continuous-Current Blower or Hand Pump, of which the following is a specification.

This invention of a continuous current blower or hand pump has for its object an easy and convenient air compressing and draft creating mechanism, which, unlike all now existing hand pumps, such as used for inflating tires, or in the form of fire-place bellows, etc., possesses the following distinctive advantages:

1.—It gives a continuous current or stream of air, instead of an intermittent one, as is the case in all now existing hand pumps.

20 2.—It is easily operated with one hand, leaving the other hand free for attending to or adjusting other things.

3.—It is compact and ornamental, with no piston rods or turning cranks projecting 25 and moving, so that it can be carried around and used in public as a fan, and at home for rapid cooling, drying, dusting, and in face massage.

It differs also from the air circulation 30 starter, forming part of my Pat. Appl. Ser. #448,060, in the following new features:

1.—The large central body of said circulation starter with the cast on flanges or rings enclosing its air inlets, is here replaced by a small size central pipe, provided 35 with four slots for air inlet ports and with a screwed on cap at each end for the compressed air discharge from either end, as may be desired.

40 2.—A separate flanged sleeve with air inlets is fastened to said central pipe.

3.—The whole mechanism of the aspirator, instead of being operated openly, like the circulation starter, is here enclosed in a stationary 45 cylindrical casing, fastened to said central pipe and provided with longitudinal slots, through which the movable cylinder is operated.

My invention consists in the above set forth novel features, embodied in the combinations and constructions hereinafter set forth and claimed and as shown on the accompanying drawings, in which like char-

acters designate the same corresponding parts in all the views. 55

Fig. 1 is a sectional elevation of my continuous current aspirator.

Fig. 2 is a side elevation of the same.

Figs. 3—4—5 are cross sections of same.

Figs. 6—7 are top and bottom views of 60 same.

Figs. 8—9 are plan views of various details.

As seen on Fig. 1, the aspirator consists of the central pipe 1, to which is soldered or 65 welded on the sleeve 2, consisting of two flanged hubs joined together by the four webs 5, as shown on Figs. 1—3—8. To fix positively the position of the sleeve on the pipe, two pins 3 pass through the pipe and 70 the hubs of the sleeve.

The open spaces between the webs 5 of the sleeve 2 communicate with the interior of the pipe 1 by the slots 4 in the pipe, as seen on Figs. 1—3. 75

On either end of the sleeve 2 is a rubber ring 6, serving as a shock absorber.

On the flanged hubs of the sleeve 2 are fitted the hollow piston 7 with its cover 8. The bottom and the cover of this hollow 80 piston are provided with the air inlet openings 9, which are closed or opened by the rubber flaps or rings 10 and 11 with the shields 12, both seated on the sleeve 2 inside the piston and clamped together between 85 the piston bottom and its cover 7—8.

Slidably fitting the outer flange of the immovably fastened hollow piston is the movable cylinder 13 with its two covers 14, whose hubs slide along the pipe 1. 90

Both covers 14 are provided with the air inlet ports 15, closed or opened by the rubber flaps or rings 16—17 with the shields 18, which are provided with ferrules slidably fitting the central pipe 1 and passing 95 through the hubs of the covers 14 and flanged over same, as shown on Fig. 1.

The sliding cylinder 13 is held up in its upward position by the spring 19 inside the upper part of the cylinder, one end of the 100 spring pressing against the upper cover 14, the other end pressing against the outer flange of the piston 7. The pocket formed between the walls of the piston and the cylinder is provided for harboring the 105 spring when the same is compressed.

The whole body of the aspirator is enclosed in the stationary casing 20, consisting of a light polished sheet metal cylinder, or of other suitable material, held in position by the two covers 21, fastened each to the central pipe 1 by the two nuts 22, screwed on to the pipe and secured against getting loose by the keys 23 and the locking washers 24, shown on Figs. 1-9, in the following 10 way: The key 23 passes through the pipe 1 and notches in into the two washers 24 and into the covers 21 of the casing 20, as shown on Figs. 1-9.

After each nut is screwed on tight, the 15 edge of the adjacent washer 24 is bent up against one of the flats of the hexagonal nuts 22. A slight groove is filed out along the bent up edge of each washer, in order to facilitate the bending, as seen on Fig. 1.

20 The extra washer plate 25, provided at the bottom cover 21, Figs. 1-2-6, is for imparting extra rigidity, as explained hereinafter.

Both ends of the central pipe 1 are provided with the screw caps 26 and 26', by 25 which each end can be closed or opened. Provision is made, as shown, for attaching the caps 26 to the covers 21 by a light hand chain (not shown on drawing).

30 The casing 20 has two or more diametrically opposite longitudinal slots 27 with the edges bent inward, as shown on Figs. 1-2, through which pass the finger grips 28 cast on to the outer surface of the movable cylinder 13.

The slits in the casing 20 below the slots 27 (slits not shown on drawing) may be left open, or can be soldered over, after the cylinder 13 with the finger grips 28 are in place.

40 The action of the aspirator is as follows: Removing one or the other of the two caps 26, placing the thumb on the rigid washer plate 25 and two fingers of the same hand on the finger grips 28, and closing thumb and fingers together, the movable cylinder 13 is pushed down and the spring 19 inside is compressed. The air in the upper part of the cylinder becomes compressed; the valves 16 and 11 will close the adjacent ports, while 45 the valves 10 and 17 will fully open, as is shown on Fig. 1, and the air from the upper part of the cylinder will be forced through the piston 7 into the central pipe 1 and out at the one of its ends from which the cap 50 26 has been removed.

Meantime the lower part of the cylinder 13 filled up with air, and when the thumb and fingers are relaxed, the compressed spring 19 will push the cylinder 13 back to 55 its upward position; the air in its lower part becomes now compressed, the valves 17 and 10 will close the adjacent ports, the valves 11 and 16 will fully open, and the air from the lower part of the cylinder will

now be forced through the cover 8 into the 65 central pipe 1 and out through the same open end.

Thus, a continuous stream of air is being discharged from the same end of the central pipe. 70

In cooling, drying, dusting, etc., the air discharge through the further end of the central pipe, at 26, will be convenient; while in face fanning and massaging the air discharge through the nearer end, at 26', will 75 be more convenient.

The small openings 29 in the top cover 21 of the casing 20, shown on Figs. 1-7, are air vents.

What I claim is:

1. A continuous current blower or hand pump, comprising a central pipe, a sleeve with two flanged hubs, a stationary hollow piston with a movable cylinder supported by a spring, a stationary casing with covers enclosing said cylinder and pipe, substantially as and for the purposes specified. 80

2. A continuous current blower or hand pump, comprising a central pipe provided with screw caps and air inlet slots, a sleeve with two flanged hubs, a stationary hollow piston with a movable cylinder, a stationary casing with covers, substantially as and for the purposes set forth. 90

3. A continuous current blower or hand pump, comprising a central pipe, and a sleeve with two flanged hubs connected together by webs and fastened to said central pipe and fixed in position by pins and communicating with the interior of said pipe by slots, a stationary hollow piston with a movable cylinder, a stationary casing with covers, substantially as and for the purpose described. 95 100

4. A continuous current blower or hand pump, comprising a central pipe, a sleeve with flanged hubs, and a stationary hollow piston enclosed by a movable cylinder fixed by a spring and provided with finger grips cast on or attached to for operating same, a stationary casing with covers, substantially as and for the purpose specified. 105 110

5. A continuous current blower or hand pump, comprising a central pipe, a sleeve with flanged hubs, a stationary hollow piston enclosed by a movable cylinder provided with finger grips, and a stationary casing with covers secured to said central pipe by double nuts with keys and locking washers and provided with longitudinal slots for sliding finger grips, substantially as and for the purpose described. 115 120

In testimony whereof, I have hereunto signed my name, at Syracuse, in the county of Onondaga, and State of New York, this 125 24th day of March, 1921.

DAVID GUELBAUM.
